ATTORNEY.

UNITED STATES PATENT OFFICE

STANLEY B. FREIBERG, OF CINCINNATI, OHIO

EASEL SUPPORT

Application filed December 16, 1926. Serial No. 155,236.

My invention relates broadly to the general class of easel supports, and particularly to a support which may be cut from a sheet of thin material such as paper.

It is the object of my invention to provide a simple easel support which may be formed from a cut and scored blank, and which, when operatively connected with an article such as a picture or sign to be displayed, may be brought into supporting position without other adjustment than the manual movement of the picture or sign to the position in which it is to be displayed. In this way, my novel easel support is what may be called automatically adjustable. It is a further object of my invention to provide an easel support which will support a picture or sign in a plurality of inclined positions depending on the particular manner in which the sign or picture is moved into inclined position for display.

Referring to the drawings in which I have shown an easel support in which are incorporated the above and other objects which will be noted in connection with the ensuing disclosure:

Figure 1 is a rear elevation of a frame to which one of my novel supports is attached.

Figure 2 is a side elevation of the frame shown in Figure 1, with the support in partially extended position.

Figure 3 is a side elevation of the frame with the support in fully extended position.

Figure 4 is a plan view of the structure shown in the same position as is shown in Figure 3.

Figure 5 is a horizontal section along the lines 5-5 in Figure 3.

Figure 6 is a plan view of the blank forming the easel support.

Referring first to the blank forming the support as shown in Figure 6, I have shown the fan shaped piece of cardboard 1 which is scored along the lines *a-a* on each side to form a flap 2 on each side, which provides a simple means for attaching the support to a picture or frame such as is indicated at 3. The score lines *b-b* are also provided, which permits the support to fold in-

wardly along these lines with a bellows fold. The support is pasted or glued to the back of the article to be displayed, the flaps 2 providing with the back of the article the engaging glued or pasted surfaces. The support has a wedge shaped portion 4, formed by the scored lines *c-c*. This portion has an elongated end extending below the lower edges of the bellows folding portions 5. When the frame is inclined to a partially inclined position as shown in Figure 2, the lower edge of the portion 4 will bear against the surface on which the frame rests, and so support the frame. When the frame is moved to a more inclined position such as is shown in Figure 3, the frame will be supported not only by the lower edge of the portion 4, but also by the lower edges of the bellows folding portions 5. I find it preferable to cut the lower edges of the bellows folding flaps so that they will provide additional support for the frame in fully extended position.

My easel support is particularly adapted for use in combination with display signs and pictures. The structure enables the support to be folded flat against the back of the frame, and the clerk can unpack and set up the frame in a position for display without adjusting the support. In moving the frame into position, the clerk has only to slide the frame at an angle to the length and width of the frame, along the surface on which it is to be displayed, and the easel support will be extended so that it will support the frame whether it be fully inclined as shown in Figure 3, or only partially inclined as shown in Figure 2.

Other uses for a support constructed in accordance with my invention will readily occur to those skilled in the art, and it will also be obvious that a similar support may be formed with the easel supporting piece an integral part of the sign or display device.

Having thus described my invention, what I claim as new and desire to secure by Letters Patent, is:

1. An easel support for an article to be displayed, cut from a unitary blank, and

comprising portions for attachment to the article, a leg portion, the lower edge of which is adapted to bear against the surface on which the article is to be displayed, and interconnecting longitudinally bellows-folding portions extended between the attaching portions and the leg portion.

5 2. An easel support for an article to be displayed, cut from a unitary blank, and comprising portions for attachment to the article, a leg portion the lower edge of which is adapted to bear against the surface on which the article is to be displayed, and interconnecting longitudinally bellows-folding portions extending between the attaching portions and the leg portion, said leg portion being of sufficient length to extend at least to the lower edge of the article to be displayed, whereby the easel support will be automatically extended with the adjustment of the article in inclined position.

10 3. An easel support for an article to be displayed, comprising portions for attachment to the article, a leg portion the lower edge of which is adapted to bear against the surface on which the article is to be displayed, and interconnecting longitudinally bellows-folding portions extended between the attaching portions and the leg portion, 25 said leg portion being of sufficient length to extend at least to the lower edge of the article to be displayed, whereby the easel support will be automatically extended with the adjustment of the article in inclined position, and the lower edges of the bellows folding portions being of sufficient length to abut the surface on which the article is to be displayed, only when the article is in fully inclined position.

30 4. An easel support formed from a blank of sheet material, said support comprising outer foldable portions for attachment to an article to be displayed, a centrally located portion having an end sufficiently long to extend at least to the lower edge of the article to be displayed when said centrally located portion is folded against the back of the article, and bellows folding portions joining the attaching portions and the centrally located portions.

35 5. An easel support formed from a blank of sheet material, said support comprising outer foldable portions for attachment to an article to be displayed, a centrally located portion having an end sufficiently long to extend at least to the lower edge of the article to be displayed when said centrally located portion is folded against the back of the article, and means connecting the attaching portions and the portion with the elongated end for limiting the outward inclination of the elongated end.

40 6. An easel support formed from a blank of sheet material comprising outer portions for attachment to an article to be supported,

a central leg portion, and intermediate bellows folding portions, said portions being articulated respectively to each other by substantially fanwise folds, said bellows folding portions adapted in effect to hinge 70 said leg portion to an article without separate attachment of said leg portion thereto, said leg adapted to support an article by the engagement of its lower edge with a surface upon which said article rests, said bellows folding portions oppositely disposed to maintain said leg in vertical alignment at a plurality of effective angles.

7. An easel support formed from a single blank and comprising a leg to operate as though hinged to an article and to support said article by the engagement of its lower end with a supporting surface, and bellows folding members extending substantially continuously between said leg and said article on both sides of said leg, said members being substantially triangular in shape and folded fanwise whereby the upper end of said leg is held close to said article while permitting said leg to be at a plurality of 90 effective angles thereto.
